MACHINE FOR TYPEWRITING ON CARTONS

Thomas C. Wornel, Cincinnati, Ohio, assignor to
Underwood Elliott Fisher Company, New York,
N. Y., a corporation of Delaware

Application November 29, 1941, Serial No. 420,903

32 Claims. (Cl. 197—3)

This invention relates to machines for typing on the outer surfaces of formed box or cartons.

Many manufacturing concerns send out to customers a large number of filled cartons of the same shape and size. In some cases thousands of such cartons are filled with samples and sent out to individuals on a mailing list.

Heretofore, in applying the addresses to such cartons, the addresses have been typed on a continuous strip of paper. This strip is cut into sections corresponding to the addresses and these sections are respectively attached to the covers of the boxes by an adhesive. The typing of the strip, the cutting of the same into sections and the attachment of the sections thus formed to the boxes involved at least three separate hand operations and consumed a great deal of labor and time.

One object of the present invention is to produce a typewriting machine by which formed boxes or cartons may be typed on the outsides thereof rapidly and efficiently.

Another object of the invention is to construct a typewriting machine arranged to type directly on the outside surfaces of formed boxes or cartons, in which the cartons are fed step by step successively into typing position, are held stationary in typing position while being typed and are successively discharged from typing position all by the action of the machine with the minimum amount of work and attention on the part of the operator.

With the above and other objects in view, the invention consists in a machine embodying the novel and improved features, constructions and combinations of parts hereinafter described and particularly pointed out in the claims, the advantages of which will be readily understood and appreciated by those skilled in the art.

The invention will be clearly understood from the accompanying drawings illustrating a machine embodying the invention in its preferred form and the following detailed description of the constructions therein shown.

In the drawings:

Fig. 1 is a plan view of a machine embodying the invention.

Fig. 2 is a view in side elevation illustrating a portion of the machine shown in Fig. 1.

Fig. 3 is a view partly in front elevation and partly in vertical section of certain parts of the machine and illustrating particularly the carton guideway or chute with the cartons therein and the carton feed mechanism.

Fig. 4 is a view similar to Fig. 3 illustrating

a portion of the mechanism shown in Fig. 3 with certain of the parts in different positions.

Fig. 5 is a view similar to Figs. 3 and 4 illustrating a portion of the mechanism shown in Fig. 3 with certain of the parts in still different positions,

Fig. 6 is a perspective view of certain parts of the machine and illustrating particularly the carton guideway or chute.

Fig. 7 is a detail view in vertical section taken transversely through the carton chute and illustrating a carton in said chute.

Fig. 8 is a detail view in vertical section taken in the median longitudinal plane of said chute and illustrating the carton chute and certain associated parts,

Fig. 9 is a perspective view of certain parts of the machine and illustrating particularly the mechanism for arresting the return movements of the carriage,

Fig. 10 is a perspective view taken from the rear of the machine and illustrating particularly the power operated mechanism for imparting return movement to the carriage,

Fig. 11 is a detail plan view illustrating the mechanism for advancing the carriage and certain parts of the carriage return mechanism,

Fig. 12 is a detail view in rear elevation illustrating the escapement mechanism for the carriage and certain parts of the column tabulator mechanism,

Fig. 13 is a detail view in side elevation illustrating certain parts of the column tabulator mechanism,

Fig. 14 is a detail plan view illustrating particularly certain parts of the column tabulator mechanism and of the carriage return mechanism,

Fig. 15 is a detail view in side elevation illustrating certain parts of the line space mechanism,

Fig. 16 is a detail view in front elevation illustrating certain parts of the line space mechanism,

Fig. 17 is a view in front elevation illustrating particularly mechanism variant from that shown in Figs. 1 and 2 for delivering the cartons to the carton chute associated with the carriage, and

Fig. 18 is a plan view of the mechanism shown in Fig. 17.

The invention is illustrated in this application as embodied in a machine of the Elliott Fisher or flat platen type, the general construction of which is illustrated and described in the patent to Foothrap No. 1,904,127, dated April 18, 1933.

The machine comprises a rectangular platen

frame having side members or rails indicated at 2 connected by cross bars 4. The flat platen is omitted in this machine and its place is taken by certain devices for guiding the cartons across the platen frame into position for typing and for thereafter guiding the cartons from the machine as they are discharged from typing position.

Upon the side rails 2 of the platen frame is mounted the usual line space frame for movement forwardly and rearwardly over said rails. The line space frame comprises the front rail indicated at 6 and the rear rail indicated at 8 extending across the side rails 2 of the platen frame and also comprises the side members 10 connecting the front and rear rails outside the rails 2 of the platen frame. The line space frame is provided with front and rear rollers 12 and 14 arranged to engage the tracks 16 formed on the side rails 2 of the platen frame to enable the line space frame to move freely over the platen frame.

Upon the front and rear rails of the line space frame is mounted a type or key carriage indicated at 18 for movement transversely of the platen frame, said carriage having front and rear rollers 19 and 21 for engaging said rails. This type or key carriage, as illustrated, carries a series of type actions such as that shown in dotted lines in Fig. 2 and indicated at 20, each of which comprises an actuating key lever 22 having a key 24 forming part of the keyboard as shown in Fig. 1. Each of these type actions also comprises a type bar 26 having a type 28 and arranged to be projected downwardly into engagement with the work and in a substantially vertical direction adjacent the end of its operating stroke. This type action is substantially the same as that illustrated and described in the patent to Foothorap No. 1,251,361 dated December 25, 1917. Instead of the manually operated type action such as that illustrated in the drawings and described above, the machine may be provided with a power driven type action such as that illustrated and described in the patent to Sundstrand on. 2,239,023, dated April 22, 1941.

The carriage is moved in an advance direction across the line space frame by means of the usual spring drum 29 journaled on the line space frame and connected with the carriage by means of a flexible band 31, preferably of metal, wound about the drum and connected with the type carriage.

The machine is provided with the usual line spacing mechanism for actuating the line space frame to move the key carriage a distance of one line space at the end of the return movement of the carriage. This line space mechanism has substantially the same construction, arrangement and mode of operation as that illustrated in the patent to Wise No. 2,248,152, dated July 8, 1941.

This mechanism comprises a transverse shaft 33 journaled in the side members 10 of the line space frame, upon which shaft the rollers 14 are mounted, and gears 34 fixed to said shaft and meshing with rack teeth 35 formed on the side rails 2 of the platen frame.

The mechanism for rotating said shaft to line space the type carriage comprises a toothed wheel 36 fixed to said shaft and a pawl 37 pivoted on an arm 38 mounted to turn on said shaft, said pawl being arranged to engage said toothed wheel. The pawl is actuated to engage the wheel and turn the same by means of bell crank 39 also mounted to turn on said shaft, one arm of which is provided with a pin 40 arranged to engage in a slot in the pawl.

The bell crank 39 is actuated to impart line

spacing movements to the shaft 33 and thereby to the line space frame through suitable connections by a draft rod 41 mounted on the line space frame between the rear rail 8 and the carriage escapement rack for longitudinal movement. This draft rod is moved to the left a predetermined uniform distance upon each return movement of the carriage as described in said Wise patent. The connections between the bell crank 39 and the draft rod for actuating the bell crank comprise a rock shaft 43 mounted in bearings in the line space frame, a lever 45 fixed to the rear end of said shaft and a link 47 connecting one arm of said lever with the bell crank 39. Said connections also comprise an arm 49 fixed to the rear end of a second rock shaft 51 mounted in bearings in the line space frame and a link 53 connecting the lever 45 with the arm 49. An arm 55 is fixed to the forward end of the rock shaft 51 and is connected by a spring 57 with a lever 59 loosely pivoted on said rock shaft. The lever 59 is actuated by means of the pawl 61 pivoted on a slide 63, mounted to slide laterally of the line space frame upon suitable guide studs and connected with the right hand end of the draft rod 41 as shown in Fig. 9, the pawl 61 carrying a pin 65 arranged to engage the upper end of the lever 59. The draft rod and the slide 63 are normally held in their right hand positions as shown in Figure 9 by means of a coiled spring 67.

The escapement mechanism of the machine preferably has substantially the construction and mode of operation of the mechanism illustrated and described in the patent to Foothorap No. 1,203,519, dated October 31, 1916. This mechanism (see Fig. 12) comprises a shaft 44 journaled on the frame of the type carriage to which is fixed a pinion 46 meshing with the teeth of the escapement rack 48 secured to the rear rail 8 of the line space frame. To the shaft 44 is also attached a toothed escapement wheel 50 and the rotation of the escapement shaft is controlled by a holding pawl 52 pivoted at 54 on the carriage frame and by a spacing pawl 56 pivoted at 58 on said frame. The holding and spacing pawls are actuated and controlled from the type bar mechanisms through the draw wire 59 to release, step by step, the escapement wheel to cause a step by step advance movement to be imparted to the type carriage by the action of the spring drum 29.

The machine is also provided with a column tabulator mechanism preferably having substantially the same construction, arrangement and mode of operation as the corresponding mechanism illustrated and described in the patent to Foothorap, No. 1,280,697, dated October 8, 1918. The column tabulating mechanism comprises a tabulator blade indicated at 60 (see Fig. 14) mounted for forward and rearward sliding movement at the rear of the carriage and a key lever 62 pivoted at 64 on the frame of the carriage and arranged, through the connections shown and described in said Patent No. 1,280,697, to control the projection of said tabulator blade rearwardly into operating position. The column tabulator lever 62 is acted upon by a coiled spring 66 which constantly tends to swing the forward end of the lever upwardly. To the portion of the lever 62 at the rear of the pivot thereof is pivotally connected the upper end of a link 68, the lower end of which is pivotally connected with an intermediate lever 70 pivoted at 72 on a bracket 74 attached to the deck of the type carriage. The other end of the lever 70 is arranged to engage the upper side of a collar 76 fixed to a vertically

movable wire or rod 78 the lower end of which is pivotally connected to one arm of a release lever 80 pivoted at 82 on a hanger suspended from the deck of the carriage. The other end of the release lever 80 is provided with a rearwardly bent portion 84 arranged to engage beneath a laterally projecting arm on the spacing dog 52.

With this construction, upon the depression of the forward end of the column tabulator lever 62, the tabulator blade 60 is projected rearwardly into operating position and the holding dog 52 is actuated to release the carriage so that the carriage advances under the action of the spring drum 29 until its movement is arrested by the engagement of the tabulator blade 60 with a co-operating fixed tabulator stop.

The tabulator mechanism also comprises a tabulator stop bar 86 supported at its ends upon the side members 10 of the line space frame and a tabulator stop 88 adjustably mounted on the bar 86 and arranged to be engaged by the column tabulator blade 60. The engagement of said blade with the stop 88 arrests the advance movement of the carriage when the column tabulator key is depressed.

The machine illustrated in the drawings also comprises power operated mechanism for returning the carriage to the left either to full return position or to either of two partial return positions to the right of its full return position after it has advanced along the line space frame in the operation of printing a line. When the carriage reaches the desired position in its return movement, the carriage is arrested by suitable stopping devices. The carriage return and stopping mechanism have substantially the same construction, arrangement and mode of operation as that illustrated and described in the patent to Oscar J. Sundstrand, No. 2,370,505, dated February 27, 1945.

The carriage return mechanism comprises a carriage return rack 90 (see Figs. 10 and 11) mounted on the rear portion of the carriage and a carriage return pinion 92 fixed to a sleeve 94 loosely mounted upon the carriage return shaft 96, said pinion meshing with the rack 90 as shown in Fig. 10. The sleeve 94 carries a driven clutch member 98 arranged to mesh with a driving clutch member 100 fixed to the carriage return shaft. The driving mechanism for the carriage return shaft comprises the intermeshing spur gears 102 and 104, the intermediate or countershaft 106, the intermeshing bevel gears 108 and 110, the transverse shaft 112, the coaxial shaft 114 connected to the shaft 112 by the coupling 116, the intermeshing spiral gears 118 and 120, the stub shaft 122, the pulley 124, the driving motor 126 having an armature shaft 128 and a belt 130 connecting the pulley 124 with a pulley 132 fixed to the armature shaft of the motor. The motor 126 may be continuously running or it may be intermittently running and controlled from the carriage return bail 150 through mechanism constructed as shown and described in the patent to Foothorap, No. 1,904,127.

The position of the sleeve 94 on the carriage return shaft is controlled to control the engagement and disengagement of the carriage return clutch by mechanism comprising an arm 134 fixed to the rock shaft 136 and having at its end a roller engaging in a groove in the sleeve, a second arm 138 on said rock shaft, a trip rock shaft 140, an arm 142 fixed to said shaft, a latch 144 loosely pivoted on the latter rock shaft and a

spring link 146 connecting the arm 138 and the latch. Upon upwardly extending arms 148 fixed to the rock shaft 140 is mounted the usual carriage return control bail 150.

5 All of the parts of the driving mechanism above described for driving the carriage return rack 90 and the carriage return control bail 150, are mounted upon the line space frame.

The mechanism for actuating the carriage return bail 150 to engage the carriage return clutch includes an arm 152 fixed to the rock shaft 154 mounted in bearings on the carriage 18 and a coiled spring 156 wrapped about said shaft and arranged to tend to turn the shaft in a direction to swing the arm 152 rearwardly. Said mechanism also includes a second arm 158 secured to the rock shaft 154, a bell crank lever 160 pivoted on a screw stud 162 threaded into one of the side plates on the carriage, said bell crank being provided with an extension 164 having a pin and slot connection with said arm 158 (see Fig. 10). A key lever 166 having a key 167 is also pivoted on the stud 162. A spring controlled by-pass pawl 168 is pivoted to said lever and arranged to engage a lip 170 on the forwardly projecting arm of the bell crank, the movement of the pawl under the action of its actuating spring being limited by a pin 172 fixed in the side plate. Through the connections described, the depression of the key 167 and the key lever 166 will swing the arm 152 and the carriage return bail 150 forwardly to cause the engagement of the carriage return clutch.

The return movement of the carriage is arrested with the carriage in full return position through the engagement of a fixed contact plate 174 (see Fig. 9) mounted on the carriage with an arrester block 176 adjustably mounted upon the draft rod 41. The return movement of the carriage is arrested with the carriage in either of two different partial return positions by the engagement of a vertically movable check stop 178 alternatively with the arrester blocks 180 and 182 also adjustably mounted on the draft rod 41. The check stop 178 is fixed to the lower end of a key bar or lever 184 having a lost motion connection at 186 with the lever 166 and provided with a key 188. The arrester blocks 176, 180 and 182 are of different heights to cooperate selectively with the contact plate 174 and with the check stop 178 which is projected downwardly to different vertical positions respectively by the depression of the keys 167 and 188.

55 The right hand end of the draft rod 41 is adjustably connected at 189 to a laterally movable slide 190 mounted to slide laterally on studs carried by the line space frame and said slide carries a projection 192 arranged to engage a stop 194 mounted on the line space frame at the right hand end of the rear rail 8. The left hand end of the draft rod is connected to a slide 196 mounted on studs carried by the line space frame to slide longitudinally with the rod and guide the same.

The carriage return bail 150 is moved rearwardly as the carriage approaches the end of its return movement to disengage the carriage return clutch by means of a slide bar 198 connected with the slide 190 by a pin and slot connection and supported in a guide 200 fixed to the line space frame. This slide bar, as the carriage approaches the end of its return movement, is moved to the left (Fig. 9) into engagement with a cam plate 202 fixed to the end of the carriage

return bail and said bail is thereby swung rearwardly to disengage the clutch.

With the above construction, upon the depression of the key 167 or the key 188 and the immediate release of the key, the carriage return clutch is engaged and the carriage will be returned to full return position at which its return movement will be arrested by the engagement of the contact plate 174 with the arrester 176. Upon the depression of the key 188 and the holding of the key in depressed position, the carriage return clutch will be engaged and the carriage will be returned to a partial return position at the right of its full return position at which its return movement will be arrested by the engagement of the check stop 178 with the arrester 180. Upon the depression of the key 167 and the holding of the key in depressed position, the carriage return clutch will be engaged and the carriage will be returned to another partial return position to the right of said first partial return position at which its movement will be arrested by the engagement of the check stop 178 with the arrester 182.

Upon the carriage return bail 150 is mounted a cam 205 adjustable longitudinally of the bail and arranged to be engaged by a tappet roll 207 mounted on a bracket 209 secured to the frame of the type carriage, said roll depending into position to engage the cam during the advance movement of the carriage.

As is well known to those skilled in the art, when the advance movement of the carriage has been arrested by the engagement of the blade 60 with the tabulating stop 88, following the depression of the forward end of the column tabulating lever 62, and said tabulating lever is released, the carriage will then execute a portion of an escape movement because of the release of the escapement wheel 50 by the spacing pawl 56 and the arrest of said wheel by the holding pawl 52 after the partial rotation of the wheel. The tabulating stop 88 is preferably located on the tabulating bar 86 and the cam 205 is located on the carriage return bail so that, when the movement of the carriage is arrested by the stop 88, the tappet roll 207 will occupy substantially the position shown in Fig. 14 with relation to the cam. Then upon the release of the tabulating lever, the escapement movement of the carriage will bring the tappet roll 207 into engagement with the cam 205. By the engagement of the roll with the cam, the carriage return bail is swung rearwardly to engage the carriage return clutch to cause the return of the carriage. The positions of the tabulating stop 88 and the cam 205 will be further described in connection with the description of the feeding of the cartons by the carriage.

The boxes or cartons 203 are conducted in succession to the typing point by means of a suitable guideway or chute mounted upon the side rails 2 of the platen frame. The right and left rails 2 of the platen frame are formed with openings 204 and 206 for the reception of the chute and the passage of the cartons. The chute is formed by two upper spaced guides 208 and two lower spaced guides 210 mounted on the platen frame in suitable positions with relation to each other and to the openings 204 and 206 to guide the cartons to and from the typing point. The cartons are each typed when located adjacent the left hand platen rail. The guides 208 and 210 preferably consist of strips of sheet metal each bent to form a right angle in cross section, the apex of which extends longitudinally of the guide.

Each of the upper guides 208 is fixed at its ends respectively to the side rails 2 of the platen frame. In the construction shown, the side wall or flange 211 of each upper chute guide is extended to pass through one of the corresponding openings 204 and 206 and is bent back over the outside of the platen rail as indicated at 212 and the extension is fixed to the platen rail by suitable fastening devices. The horizontal wall or flange 214 at the top of each of these chute guides is terminated at the inside walls of the rails 2 of the platen frame.

The horizontal flanges 214 of the guides 208 are spaced from each other preferably a distance sufficient to permit the writing of a four line address by the type engaging a carton between these flanges.

The two lower guides 210, forming the carton chute, are positioned between the side flanges 211 of the upper guides 208. The lower guides are mounted in spaced relation in the opening 204 in the right hand platen frame rail 2 and their left hand ends terminate some distance inside the left platen rail. These guides rest upon the bar portion 216 of the right hand platen rail at the bottom of the opening 204 and preferably project some distance to the right beyond said opening to the outside of the platen rail as clearly shown in Figs. 3 to 6 inclusive. The chute guides 210 are held in spaced relation by means of strips 218 secured to the horizontal flange 220 of each guide, as shown clearly in Fig. 7, each strip having a bowed formation between the rails as shown in this figure. One of these strips is located just inside the bar portion 216 of the right hand platen rail as shown in Fig. 8, which holds the guides 210 against substantial movement from left to right. In order to support yieldingly the left hand ends of the guides 210, coiled springs 222 are attached at their lower ends to the extremities of the left hand strip 218 and at their upper ends to pins or studs fixed to the guides 208.

In order to prevent any right to left movement of the guides 210, the retaining brackets 224 are secured to these guides and arranged to engage the bar portion 216 of the platen rail as shown in Fig. 8. The chute guides 208 and 210 are preferably positioned with relation to each other so that the space between the side flanges of the lower guides is slightly greater than the width of the boxes or cartons which are fed through the same but so that the distance between the bottom and top flanges of the guides is considerably greater than the depth of the boxes at the right hand end of the chute.

The cartons are fed into the carton chute preferably by a feeding mechanism which constantly exerts a yielding tendency to force the cartons through the chute. In the present construction, the mechanism for feeding the cartons to the carton chute comprises an endless belt which engages the cartons frictionally and operates continuously to tend to force the cartons through the chute. In the construction shown in Figs. 1 and 3, the cartons are fed to the carton chute by means of a feed belt 226 passing about pulleys 228 and 229 and operating to feed the cartons forward between the guide plates 230 between which the belt runs. The delivery belt may constitute the only conveyor employed upon which the cartons are placed manually or it may consist of part of a conveyor system of the plant in which the machine is installed to which the cartons are delivered by other conveying means.

The feed belt 226 is mounted upon drums or pulleys 228 and 229 of which the drum 229 is fixed to a shaft 231 mounted in suitable bearings (not shown). The drum 228 is fixed to a shaft 233 mounted in bearings in brackets 235 and 237 attached to the right hand side rail 2 of the platen frame. Upon the rear end of the shaft 233 is secured a gear 239 meshing with a pinion 241 fixed to the armature shaft 245 of an electric motor 247 mounted on a bracket 249 attached to the frame of the machine. The gears 241 and 239 have a speed reducing ratio so that the shaft 233 and the feed belt 229 are driven at a relatively slow speed compared with the speed of the armature shaft of the motor. The cartons rest upon the belt 229 between the guide plates 230 and are held in frictional contact with the belt by gravitational action on the cartons. By the action of the feed belt the cartons 203 are fed successively into the right hand end of the carton guide chute and are forced along said chute toward the left hand end thereof. The motor 247 is a continuously running motor and the belt 229 acts continuously on the cartons, tending to feed the same into and through the chute.

The bearings for the shaft 231 of the drum 229 and the side guide plates 230 may be supported in any suitable manner either from the framework of the machine or otherwise.

In order to arrest each of the cartons 203 in typing position as it is fed through the carton guide of the machine, a beveled face indicated at 232 is formed on the left hand platen rail 2 upon the portion thereof just above the discharge opening 206. The chute guides 208 are secured to this left hand platen rail so that the lower surface of the top or horizontal flange of each of the chute rails lies in a plane preferably slightly below the upper termination of this beveled face 232 on the inside of the platen rail. As the cartons are fed through the carton chute, the upper left hand corner of each carton, arriving at typing position, engages the beveled face 232 and its movement is arrested by its engagement with this face. The friction of this corner of the carton against the beveled face 232 is sufficient to arrest the movement of the carton through the chute under the frictional action of the conveyor 226.

The carton upon which the typewritten matter has been completed is discharged from typing position and the succeeding carton is fed into typing position by means of a feeding device which acts positively on these two cartons. After the typewriting on a carton has been finished, the column tabulator lever 62 is actuated to tabulate the carriage to the right until its movement is arrested by the engagement of the tabulating blade 60 with the tabulating stop 88. The release of the tabulating lever 62 then allows the carriage to execute the latter part of an escape movement and this movement of the carriage throws in the carriage return mechanism to return the carriage to full return position. This return movement of the carriage is used to feed the carton upon which the typing has been completed, out through the discharge opening 206 and to feed the succeeding carton into typing position.

This positive feeding mechanism comprises a feed finger or pawl 234 pivoted at 236 to a hanger mounted on the deck 238 of the carriage and arranged to engage the right hand end of each of the cartons as shown in Fig. 3 to feed the same through the chute. This feed finger, as shown, is shaped and mounted so that the acting end there-

of is held downwardly by the weight of the corresponding arm. During the advance of the carriage in typing, however, the feed finger rides on the top of the second carton or the one to the right of the carton being typed as shown in Fig. 4. The downward movement of the feed finger under the action of gravity, when no cartons are in the machine, is limited by the engagement of a shoulder 240 on the finger with the deck 238 as shown in Fig. 3.

As stated above, the upper and lower walls of the carton chute are spaced, at points adjacent the right hand platen rail 2, by a distance considerably greater than the depth of each of the boxes. In order to locate the rear end of the second carton in the chute in position to be engaged by the feed finger 234, a leaf spring 242 is secured to the bottom flange 220 of the forward guide 210 and is arranged to project obliquely upwardly between said guides as shown in Figs. 3 and 6, this spring being preferably shaped as shown in these figures. As the cartons are fed through the carton chute, the spring 242 will engage the under side of each carton and lift the same. This spring is positioned so that when a carton is located in typing position and the next or second carton has been fed forwardly into contact with the first carton, the rear end of the second carton will be located at substantial distance 30 above the forward end of the third carton.

The tabulating blade 60 and the tabulating stop 88 are located so that the tabulation of the carriage to the right after the completion of the typing operation upon a carton, carries the feed finger 234 beyond the right hand end of the second carton 203 into a position such as that shown in Fig. 5, the feed finger then resting on the third carton. Then when the carriage return mechanism is thrown into operation in the manner 35 described upon the release of the tabulating lever 62, the feed finger 234 will engage the right hand end of the second carton and force the same to the left. The force exerted by the feed finger causes the upper left hand corner of the first carton to slide downwardly along the inclined face 232 of the left hand platen rail, the springs 222 then allowing the portions of the lower guides 210 of the carton guide chute to the left of the right hand platen rail 2 to swing downwardly 40 about the bar portion 216 of the said platen rail into substantially the positions shown in dot and dash lines in Fig. 3 to permit the discharge of the left hand carton through the opening 206. When the right hand upper corner of the first carton 55 passes beyond the inclined face 232, the carton is projected through the opening 206 into any suitable receptacle that may be placed below the same. After the discharge of this carton, these guides 210 swing back under the tension of the 60 springs 222 to their normal positions shown in Fig. 4 and in full lines in Fig. 3. The movement of the carriage carries the second carton into position to be typed as shown in Fig. 3 so that the forward upper corner of the carton engages 65 the contact face 232, or substantially to this position, the mechanism for arresting the carriage in full return position being preferably arranged to stop the carriage movement when the carriage has reached a position to locate the first carton 70 in typing position.

The movement of the second carton under the influence of the feed finger 234 will produce a space between the same and the third carton but this space is immediately filled up by the feed 75 movement of the cartons at the right of the sec-

ond carton under the frictional action of the belt 226 which, as stated above, constantly tends to feed the cartons through the carton guide. If the feed finger does not bring the second carton quite to typing position, the feeding action of the feed belt will force it along the chute until its left hand upper corner engages the inclined face 232.

In order to limit the forward and rearward movement of the line space frame over the platen rails 2, and thereby maintain the typing point within the typing positions on the carton, a bracket 242a is secured inside the right hand platen rail and is provided with two spaced upwardly projecting fingers 243 embracing the cross bar or rod 244 on the line space frame. By the engagement of this cross rod with these fingers respectively, the forward and rearward movements of the line space frame are limited preferably to about the distance required for a four line address.

The motor 126 is provided with circuit connections, with a cut off switch and with a safety bail 246 for controlling said switch, all preferably constructed and arranged as shown and described in the patent to Oscar W. Swanson, No. 2,270,391, dated January 20, 1942. In order to prevent a power operation of the line space mechanism when the rod 244 is engaged with the forward line space frame stop finger 243, an arm 248 is secured to the left hand platen rail 2 and projects upwardly beyond said rail into position to engage the safety bail 246 when the line space frame is moved forwardly from the position it assumes in writing the fourth line of an address. This arm is located so that, as the line space frame is moved forwardly from this position, said arm engages the safety bail to disconnect the motor circuit just before the rod 244 engages the forward stop finger 243.

The guides 208 of the carton chute are preferably located so that the upper surface of the carton, when in typing position, is held slightly above the normal typing plane to allow for the give of the carton top when engaged by the type. The carton, in typing position, is held yieldingly against the top walls or flanges 214 of the guides 208 by the left hand ends of the lower guides 210 under the action of the spring 222.

The above described mechanism has the following mode of operation: Assuming that the left hand carton 203 is in position for typing with its left hand upper corner held against the beveled face 232 by the feeding action of the feed belt 226, the operator types the first line of the address on the top or cover of the carton and then depresses and immediately releases either of the carriage return keys 188 or 167 to cause the return of the carriage to the left hand full return position as determined by the arrester 176 and the line spacing of the carriage. The operator then types the second line of the address and thereafter again depresses and immediately releases either of said carriage return keys to cause the return of the carriage again to its full return position as determined by the arrester 176, and the line spacing of the carriage. He then types the third line of the address, thereafter pushes the machine head back to its limiting rear position and depresses the forward end of the column tabulator lever 62. During the letter spacing movements of the carriage in typing the several lines of the address, the feed finger or pawl 234 rides on the top of the carton 203 to the right of the carton in typing position. The

actuation of the column tabulator lever causes the carriage to tabulate to the right until the tabulator blade 60 engages the tabulator stop 88 to arrest the carriage movement. This brings the carriage into substantially the position shown in Fig. 5 in which the feed finger has been carried beyond the elevated end of the second carton 203 or the one to the right of the carton in typing position and said finger has dropped down into engagement with the succeeding or third carton. The column tabulator lever is then released and the slight advance of the carriage resulting therefrom causes the carriage return mechanism to be thrown into operation by the engagement of the tappet roll 207 with the cam 205 and the carriage is returned to its full return position. During this return movement, the feed finger engages the rear end of the carton to the right of the one in typing position and both cartons are fed forward positively by the return of the carriage, thereby discharging the typed carton through the discharge opening 206 and moving the succeeding carton up to or substantially up to typing position. The action of the feed belt then closes the gap between the first and second cartons. If the feeding movement of the feed finger does not bring the forward upper corner of the first carton into engagement with the beveled face 232 on the left hand rail 2, the action of the feed belt will crowd this carton up against said beveled face.

This series of operations is then repeated in typing and discharging the succeeding cartons.

With the proper adjustment of the arresters 176, 180 and 182, the three lines of the address may be typed with different margins if the carton provides sufficient space, by the actuation of the keys 189 and 167 to cause the return of the carriage to different partial return positions respectively after typing the first and second lines.

Figs. 17 and 18 illustrate a form of the mechanism for feeding the cartons to the carton chute in which the principal parts are supported upon the framework of the machine and may be set up with said machine as a unit. In the construction shown in these figures, the cartons are fed to the carton chute by means of an endless conveyor 252 mounted upon drums or pulleys 254 and 256 and operating between side plates 258 which guide the cartons between them. The drum 254 is fixed to a shaft 260 mounted to turn in bearings formed upon brackets secured to the right hand platen rail 2, one of which brackets is shown at 262. The shaft 260 is driven to drive the conveyor by means of a motor 264 mounted upon a bracket 266 secured to the side member 268 of the pedestal of the machine and the motor is connected to the shaft 260 by suitable gearing such as that shown in Fig. 1 by which the shaft 260 is driven at a relatively slow speed compared with that of the armature shaft of the motor.

The drum 256 is fixed to a shaft 270 mounted to turn in suitable bearings carried by the spaced supporting frame members 272, the lower ends of which (not shown) are fixed to the pedestal 268 of the machine. The left hand ends of the side plates 258 are attached to the right hand platen rail 2 on the outside of the respective projecting end portions of the lower guides 210 of the carton chute as clearly shown in Fig. 18, the said end portions of the guides 210 moving vertically between said side plates 258 during the

vertical swinging movements of the guides about the bar portion 216. Fig. 17 shows the position of the lower guides of the chute with relation to the belt whereby the cartons are delivered by the belt between said guides. To compensate for the vertical movement of the right hand ends of the guides 210, the bottom wall 220 of each of said guides is bent downwardly adjacent the right hand ends of the guides as indicated in Fig. 17.

In order to prevent undue sagging of the upper run of the belt 252 a supporting plate 274 is mounted below said run upon brackets 276 attached to the side plates 258.

To the right hand ends of the side plates 258 is attached an inclined chute indicated as a whole at 278. This inclined chute comprises spaced side plates 280 and a bottom plate 282 to which said side plates are attached. The side plates 258 are connected to the lower ends of the side plates 280 of the inclined chute by means of brackets or plates 284. The upper end of the inclined chute 278 is supported upon the inclined frame members 272 which are extended upwardly beyond the shaft 270 and are secured in any suitable manner to the side plates 280 at the upper end of the chute.

The cartons 203 are preferably assembled upon a substantially horizontal assembly table indicated at 206 upon which is a guideway or trough indicated as a whole at 208 within which the 30 cartons are placed. This guideway comprises side plates 290 and a bottom plate 292 to which the side plates are attached. The left hand end of the guideway 208, as shown in Figs. 17 and 18, preferably is detachably secured to the upper end of the inclined chute 218 in position to deliver the cartons from the guideway 208 into the inclined chute. In the construction shown, the side plates 290 of the chute 218 are detachably secured to the side plates 290 of the guideway 208 by means of brackets or plates 294, these brackets being attached to the plates 290 by means of removable screws 296.

With the construction shown, the cartons are assembled by a workman within the horizontal guideway or trough 288 and are slid along to the left in said guideway successively to deliver the same into the inclined chute 276. The cartons pass from the inclined chute on to the conveyor 252 by which they are carried into the receiving end of the carton chute mounted upon the platen side rails.

In order to maintain sufficient friction between the cartons and the conveyor 252 to feed the cartons in a reliable manner between the guide plates 258, a roller 298 is mounted upon the side plates 258, upon supporting arms 300 pivoted respectively to said side plates and the roller is pressed yieldingly down upon the tops of the cartons as they are fed along by the conveyor by means of coiled tension springs 302 attached at their ends respectively to one of the side plates and to one of the supporting arms. This roller preferably is covered with rubber and exerts a substantial pressure against the cartons as they are fed beneath the same.

It is to be understood that the invention is not limited to the form thereof illustrated and described in this application or to the particular construction and arrangement of parts in which it is shown as embodied, but that the invention may be embodied in other forms and may include other constructions with the scope of the claims.

It is to be understood that the term "carton," employed in the specification and claims of this

case, designates a hollow container having substantial thickness and having side walls, and one or more walls spanning the side walls, to form an enclosure as distinguished from a carton blank. The cartons may be empty or filled with merchandise for shipment.

Having explained the nature and object of the invention and having illustrated and described a construction embodying the invention in its preferred form, what is claimed is:

1. A typewriting machine for writing on cartons comprising a carton guide having opposite side walls and a bottom wall along which loose disconnected cartons are arranged to slide in a train with side walls in contact, type mechanism, means for supporting the carton guide and type mechanism for relative movement to transfer the typing point in one direction, step by step, across the cartons and to return the type mechanism in the opposite direction to starting position with relation to the carton guide, and means operated by the relative return movements of the type mechanism and carton guide for engaging successively cartons in the midst of said train to feed the same successively along the guide.
  2. A typewriting machine for writing on cartons comprising a carton guide having opposite side walls and a bottom wall along which loose disconnected cartons are arranged to slide in a train with side walls in contact, a type carriage movable with relation to the carton guide in one direction to transfer the typing point, step by step, across the cartons and in the opposite direction to return the type carriage to starting position and means operated by the return movements of the type carriage for engaging successively disconnected cartons in the midst of said train to feed the same successively along the carton guide.
  3. A typewriting machine for writing on cartons comprising type mechanism, a carriage movable in letter spacing and return directions, a carton guide having opposite side walls and a bottom wall along which loose disconnected cartons are arranged to slide in a train with side walls in contact, a feed device on the carriage arranged to engage the rear end of a carton during the return movement of the carriage and means for placing said carton in position for engagement of the feed device therewith.
  4. A typewriting machine for writing on cartons comprising type mechanism, a carriage movable in letter spacing and return directions, means for guiding the cartons into position to be typed, a feed device on the carriage arranged to engage the rear end of a carton during the return of the carriage and means for raising the rear end of said carton to position the same for the engagement of the feed device therewith.
  5. A typewriting machine for writing on cartons comprising a carton guide and type mechanism relatively movable to transfer the typing point, step by step, across the machine, power means for relatively moving the type mechanism and the carton guide in return directions, means operated by the relative return movements of the type mechanism and carton guide for feeding the cartons along the guide and a conveyor for constantly urging the cartons along the guide.
  6. A typewriting machine for writing on cartons comprising a carton guide, a type carriage mounted for movement in letter spacing and return directions, power means for returning the carriage, means operated by the return movement of the type mechanism for feeding the car-

tons along the guide and a conveyor for constantly urging the cartons along the guide.

7. A typewriting machine for writing on cartons comprising a carton guide and type mechanism relatively movable to transfer the typing point, step by step, across the machine, power means for relatively moving the type mechanism and the carton guide in return directions, means operated by the relative return movement of the type mechanism and carton guide for feeding the cartons along the guide, a conveyor for constantly urging the cartons along the guide, and means for holding the cartons stationary during typing.

8. A typewriting machine for writing on cartons comprising a frame, a carton guide and type mechanism relatively movable to transfer the typing point, step by step, across the machine, power means for relatively moving the type mechanism and the carton guide in return directions, means operated by the relative return movement of the type mechanism and carton guide for feeding the cartons along the guide and an inclined contact face on the frame arranged to be engaged by the foremost carton to hold the carton stationary during typing, the guide having a portion movable to release the foremost carton from said contact face and allow the cartons to pass along the guide.

9. In a typewriting machine, typewriting mechanisms, a platen constructed to support cartons during the typing of the same, means for supporting the typewriting mechanisms and platen for relative movement in letter-spacing and return directions, means for moving relatively said typewriting mechanisms and said platen to letter space and means for feeding cartons successively along said platen into and out of typing positions comprising mechanism tending constantly to feed the cartons along the platen, a device for holding the cartons stationary against the action of said feeding means during the typing of each carton, and mechanism for causing the release of the cartons from said holding device.

10. In a machine of the class described, the combination with a carton support and printing mechanism, relatively movable longitudinally of the lines of writing, mechanism tending constantly to feed disconnected cartons along the carton support and means for positively feeding the cartons successively to the carton support by such relative movement of the carton support and printing mechanism.

11. In a machine of the class described, the combination with a fixed carton support for supporting cartons successively during the typing of the same, typewriting mechanism and a carriage having advancing movement during the typing of a carton and retracting movement longitudinally of the lines of writing, of means whereby such retracting movement of the carriage will feed a carton off the carton support and another into position to be typed and mechanism for feeding disconnected cartons into position to be acted upon by the latter means.

12. A typewriting machine comprising a substantially flat platen, a platen frame, a line-space frame movable forwardly and rearwardly over the platen frame, a type carriage movable on the line-space frame in letter-spacing direction and return, a carton guide mounted on the platen frame through which disconnected cartons pass in a train with side walls in contact, a feed device carried by the type carriage

and arranged to engage successively said disconnected cartons to feed the same along the carton guide and means for positioning for engagement with the feed device the cartons in the midst of the train successively with relation to other cartons in said train.

13. A typewriting machine for writing on cartons comprising a platen for cartons and type mechanism relatively movable to transfer the typing point, step by step, across the cartons and to return the type mechanism to starting position with relation to said platen, a friction feed for the cartons for urging the cartons constantly toward typing position and a positive feed for forcing each carton positively into position to be typed and for causing the discharge of the typed carton.

14. A typewriting machine for writing on cartons comprising a platen for cartons and type mechanism relatively movable to transfer the typing point, step by step, along the cartons and to return the same to starting position with relation to said platen, a friction feed for the cartons constantly urging the cartons forwardly over the platen and a feed finger for engaging the cartons successively to feed the same positively into typing position and to cause the discharge successively of the typed cartons.

15. A typewriting machine for writing on cartons comprising a carton support and type mechanism relatively movable to transfer the typing point, step by step, along the cartons and to return the type mechanism to starting position with relation to said support, a friction feed for constantly urging the cartons forwardly along the support, means for successively stopping the cartons in typing position against the action of said friction feed and a positive feed for feeding the cartons against the action of the stopping means.

16. A typewriting machine for writing on cartons comprising a carton support and type mechanism relatively movable to transfer the typing point, step by step, across the cartons and to return the type mechanism to starting position with relation to said support, a friction feed for the cartons to urge the same constantly toward typing position, a friction stop against which the carton in typing position rests and a positive feed for the cartons for forcing a typed carton past the friction stop and for feeding the succeeding carton into typing position substantially into engagement with said stop.

17. A typewriting machine for writing on cartons comprising a carton support and type mechanism relatively movable to transfer the typing point, step by step, along the cartons and to return the type mechanism to starting position with relation to the support, a friction belt for constantly urging the cartons frictionally along the support toward typing position, an inclined stop frictionally engaged by the carton in typing position to hold the same from feeding movement under the action of said belt during the typing operation and a positively acting feed finger for engaging the cartons successively to force the typed carton along said stop into discharging position and to feed a succeeding carton into position to be typed substantially in engagement with said stop.

18. A typewriting machine for writing on cartons comprising a guide chute having a fixed section, and a second section mounted for movement toward and from the fixed section and

yieldingly pressed toward the fixed section, a friction feed tending to feed the cartons through the chute, a retaining device for holding the cartons in typing position against the action of said friction feed from which position the cartons are released upon the movement of the movable section of the chute away from the fixed section and a positive feed for the cartons to force the cartons against the retaining device and thereby cause a movement of the movable section of the chute away from the fixed section to release a carton then in typing position.

19. A typewriting machine for writing on cartons comprising a carton-feed chute having a fixed section and a movable section yieldingly pressed toward the fixed section, type mechanism movable with relation to the carton chute to transfer the typing point, step by step, along the cartons and to return the type mechanism to starting position, a friction belt for forcing the cartons frictionally along the chute to maintain one of said cartons in typing position, a platen frame having an inclined face arranged to be engaged by the carton in typing position to hold the same against the action of said friction belt and a feed member movable with the type mechanism for engaging the cartons successively and forcing the same positively along the chute to cause the disengagement of the carton in typing position from said inclined face and the discharge of the same from the machine and the movement of the succeeding carton into typing position substantially in engagement with said face.

20. In a writing machine of the flat platen type, a platen frame, a type carriage supported on said frame for letter spacing and return movements, type mechanism mounted on the carriage, means for guiding cartons into and out of position to be typed by the type mechanism comprising one or more fixed carton guides attached to the platen frame and one or more carton guides located in opposed relation to said first guides and movable toward and from said first guides, means for yieldingly pressing the latter guides toward said first guides, means constantly tending to feed the cartons through said guides and means for positively feeding the cartons into and out of typing position.

21. In a writing machine of the flat platen type, a platen frame, a type carriage supported on said frame for letter spacing and return movements, type mechanism mounted on the carriage, means for guiding cartons into and out of position to be typed by the type mechanism comprising one or more fixed carton guides attached to the platen frame and one or more carton guides, located in opposed relation to said first guides and movable toward and from said first guides, means for yieldingly pressing the latter guides toward said first guides, an endless belt for engaging the cartons, means for actuating the belt to cause the belt to tend to feed the cartons constantly through the guides and a feed finger on the carriage for positively feeding the cartons through the guides.

22. In a writing machine of the flat platen type, a platen frame, a type carriage supported on said frame for letter spacing and return movement, type mechanism mounted on the carriage, means for guiding cartons into and out of position to be typed by the type mechanism comprising one or more fixed carton guides attached to the platen frame and one or more carton guides

5 located in opposed positions with relation to said first guides and movable toward and from said first guides, means for yieldingly pressing the latter guides toward the first guides and means for feeding cartons successively through the guides.

10 23. In a writing machine of the flat platen type, a platen frame, a type carriage supported on said frame for letter spacing movement and return movement, type mechanism mounted on the carriage, means for guiding the cartons into and out of position to be typed by said type mechanism comprising a carton guide for guiding disconnected cartons in a train with side walls of the same in contact, means on the carriage for engaging cartons successively in the midst of said train to feed the same and mechanism for placing cartons in the train successively in position to be engaged by said means on the carriage.

15 24. A typewriting machine for writing on cartons comprising a carton support and type mechanism relatively movable to transfer the typing point, step by step, along the cartons and to return the type mechanism to starting position with relation to said support, mechanism for constantly urging the cartons forwardly along the support, means for successively stopping the cartons in typing position against the action of the latter mechanism and a positive feed for feeding the cartons against the action of the stopping means.

20 25. A typewriting machine for writing on cartons comprising a carton support and type mechanism relatively movable to transfer the typing point, step by step, across the cartons and to return the type mechanism to starting position with relation to said support, feeding mechanism for the cartons to urge the same constantly 25 toward typing position, a friction stop against which the carton in typing position rests and a positive feed for the cartons for forcing a typed carton past the friction stop and for feeding the succeeding carton into typing position substantially into engagement with said stop.

25 26. A typewriting machine for writing on cartons comprising a carton support and type mechanism relatively movable to transfer the typing point, step by step, along the cartons and to return the type mechanism to starting position with relation to the support, means for constantly urging the cartons frictionally along the support toward typing position, an inclined stop frictionally engaged by the carton in typing position to hold the same from feeding movement under the action of said means during the typing operation and a positively acting feed finger for engaging the cartons successively to force the type carton along said stop into discharging position and to feed a succeeding carton into position to be typed substantially in engagement with said stop.

30 27. A typewriting machine for writing on cartons comprising a carton guide-chute, type mechanism movable with relation to the carton chute to transfer the typing point, step by step, along the cartons and to return the type mechanism to starting position, said chute comprising relatively movable sections, feeding mechanism tending to move the cartons constantly along the guide chute, a retaining device for holding the cartons in typing position against the action of said feeding mechanism from which position the cartons are released upon relative movement

of the sections of said chute away from each other and a positive feed to force the cartons forward against the action of said retaining device and thereby cause relative movement of the sections of the chute away from each other to release the cartons.

28. A typewriting machine for writing on cartons comprising type mechanism, a carriage movable in letter spacing and return directions, a carton guide for guiding cartons in a train with side walls in contact into position to be typed, a feed device arranged to engage the rear end of a carton in the midst of the train and means for raising the rear end of said carton to position the same for the engagement of the feed device therewith.

29. A typewriting machine for writing on cartons comprising a carton guide and type mechanism relatively movable to transfer the typing point, step by step, across the machine, power means for relatively moving the type mechanism and the carton guide in return directions, means operated by the relative return movements of the type mechanism and carton guide for feeding the cartons along the guide and means for constantly urging the cartons along the guide.

30. A typewriting machine for writing on cartons comprising a carton guide and type mechanism relatively movable to transfer the typing point, step by step, across the machine, power means for relatively moving the type mechanism

and the carton guide in return directions, means operated by the relative return movement of the type mechanism and carton guide for feeding the cartons along the guide, means for constantly urging the cartons along the guide, and means for holding the cartons stationary during typing.

31. A typewriting machine for writing on cartons comprising a frame, a carton guide and type mechanism relatively movable to transfer the typing point, step by step, across the machine, power means for relatively moving the type mechanism and the carton guide in return directions, means for feeding the cartons along the guide and an inclined contact face on the frame arranged to be engaged by the foremost carton to hold the cartons stationary with relation to the guide during typing.

32. A typewriting machine for writing on cartons comprising a platen for supporting cartons and type mechanism relatively movable to transfer the typing point, step by step, across the cartons and to return the type mechanism to starting position with relation to said platen, feeding mechanism for urging yieldingly the cartons constantly toward typing position and a positive feed for forcing each carton positively into position to be typed and for causing the discharge of the typed carton.

THOMAS C. WORNEL.
